UNITED STATES PATENT OFFICE

2,608,931

ROCKET

Charles C. Lauritsen, Pasadena, Calif., assignor to
the United States of America as represented by
the Secretary of the Navy

Application March 1, 1946, Serial No. 651,299

3 Claims. (Cl. 102—49)

1

This invention relates to rocket projectiles and has particular relation to rockets provided with a head structure containing an explosive and a fuze responsive to pressures generated by burning of the propellant in the motor tube.

Although use of the invention is not limited to any particular rocket projectile, it has found particular use in rockets of the type disclosed in copending application Ser. No. 652,439, assigned to the same assignee as is the present invention.

One object of the invention is to provide a rocket which is capable of carrying as a pay load any one of several types of head structures closely resembling in function and operation the various gun projectiles such as fragmentation, armor-piercing, chemical shells etc. and which may employ either or both nose and base fuzes.

Another object of the invention is to provide a rocket which provides a simple and effective means of detachably connecting the motor tube and the pay load or head structure.

A further object of the invention is to provide in a rocket projectile having a nose or war head structure containing a pressure operated fuze, means for detachably mounting the head structure onto the motor tube, and means for normally sealing the motor tube from the head structure, said means being rupturable upon burning of the propellant for exposing the fuze to the pressure of the propellant gases.

In amplification of the latter statement, it is an important object of the invention to provide a combined sealing and rupturable diaphragm which seals the end of the rocket motor tube opposite to the nozzle against the access of moisture to the propellant charge during storage and shipment, and ruptures to permit the escape of pressure gas either in the event of the inadvertent ignition of the propellant charge during storage and shipment, or to permit said escape to actuate the fuze of the ultimately attached war head when the projectile is in flight.

These and other objects of the invention will be better understood by reference to the following description and accompanying drawing, in which

The single figure is an elevational view of a rocket incorporating a preferred embodiment of the present invention, with portions thereof broken away and in section.

Referring to the drawing, the rocket includes a motor tube 10 which is internally threaded at its forward end 11 to support a nose or head structure 12 which functionally may be similar

to a fragmentation, armor-piercing or chemical shell etc. The head structure has a rear end portion 13 of reduced diameter which slips within the forward end 11 of the motor tube 10 and is threaded for attachment thereto as at 14. The head structure is provided with a suitable nose fuze 15 which may be conventional, and the base end is provided with a base fuze 16 preferably of the type shown in copending application Ser. No. 576,119, assigned to the same assignee as is the present invention. Fuzes of this type are designed to be armed by the pressure generated in the rocket motor.

The rear end 13 of the head structure is positioned within the motor tube 10 which is closed by a diaphragm 20 secured around its rim to the interior wall of the motor tube. The diaphragm is mounted between felt packing washers 21 and 22. The washer 22 is carried by the diaphragm. For this purpose use is made of the centrally located annular flange 17 which, because of being erected from the diaphragm 20 toward the burnable charge 24, provides a shoulder on which the washer is fitted in contact with the diaphragm and said charge. The edge of this flange is turned in and has the periphery of the disk 23 crimped upon it. The diaphragm 20 has a central opening in which a blow-out disk 23 is fitted tightly as indicated but is adapted to give way when a predetermined pressure is generated in the rocket motor in order that this pressure be available to arm the base fuze 16. An additional purpose of the rupturable diaphragm, in other words the diaphragm 20 with its blow-out disk 23, is to (1) seal the motor tube 10 during shipment and (2) provide a relatively safe gas escape in case of an inadvertent detonation of the igniter 24 and consequent ignition of the powder grain 27. Adjacent the diaphragm 20 is an igniter 24 comprising a case containing one or more electrical squibs (not shown) and a charge of ignition powder such as black powder. The squibs are connected to a source of electrical current by means of the terminal 25 and the conducting wires 26 which lead out the rear end of the motor tube. The remaining portion of the motor tube is filled with a propellant grain 27 preferably in the form of a single extruded member, in this case of cruciform cross section. It will be noted that the packing washers 21 and 22 tend to compensate for variations in length of the propellant charge caused by changes in temperature.

The rear end of the motor tube is closed by a suitable nozzle arrangement (not shown), preferably of the construction disclosed in copending

application Ser. No. 652,439, assigned to the same assignee as the present invention. Several fin plates 30 are secured to the rear end portion of the motor tube. Formed fin plates are ordinarily used and they are preferably of the construction shown in my copending application Ser. No. 652,439, assigned to the same assignee as the present invention. Rockets of this type may be launched from various types of launchers. If the rocket is to be fired from an aircraft, a launcher of the type generally known as "zero-length" is employed, inasmuch as with such a launcher the rocket acquires full flight after moving only a nominal distance. For cooperation with such a launcher, the rocket is provided with a forward button lug 31 and a rearward loop strap 32.

In operation, the rocket, if fired from a moving aircraft, is suspended from the launcher by means of the lug 31 and strap 32. The wires 26, which lead out the rear end of the rocket, are connected to a source of electrical current (not shown). The electrical current ignites the squib or igniter 24 which initiates combustion of the propellant grain 27. When the generated gases reach a predetermined pressure, the blow-out disk 23 is ruptured thereby exposing the pressure operated base fuze 16 to the propellant gases whereby the base fuze 16 is actuated to detonate an explosive in the war head 12 or arm the nose fuze 15.

It will be apparent that the war head 12 is readily detachable from the motor tube 10 without exposing the propellant grain 27 to moisture or ignition hazards; that is, the propellant grain remains sealed during an interchange of warheads. At such times, and during storage of the motor tube the diaphragm 20 with its rupturable portion 23 serves as a safety accessory. If by a remote chance the burnable charge should become ignited, for example by ambient high-frequency electronic waves or currents induced in the internal wiring, the portion 23 would rupture simultaneously with the jet discharge at the nozzle and thus reduce the pressure immediately so that burning will not be sustained.

It will also be apparent that the blow-out disk 23 may be so constructed as to withstand accidental ignition of the igniter 24 and yet submit to fracture by the pressure of the propellant gases. Thus, in the event that the igniter fails to ignite the propellant, the blow-out disk will prevent premature actuation of the base fuze. In addition, the blow-out disk may be constructed so as not to be ruptured by pressures caused by a partial burning of the propellant grain.

The invention herein described may be manufactured and used by or for the Government of the United States of America for governmental purposes without the payment of any royalties thereon or therefor.

I claim:

1. In a rocket projectile having a motor tube containing a propellant and a head structure detachably mounted thereon, said head structure containing an explosive and having a fuze actuatable by pressure of propellant gases from said motor tube on ignition of said propellant; means for assuring sealing of said motor tube in the possible absence of the head structure, said means comprising a diaphragm secured to the motor tube, separating said propellant from said head structure and having an opening therein, and a blow-out disk normally sealing said opening and adapted to be ruptured by said gases to establish communication between said motor and said fuze upon ignition of said propellant.
2. In a rocket projectile having a motor tube containing a burnable charge confronting a jet nozzle at one end; a safety accessory at the other end of the tube primarily effective during the storage and shipment of the motor tube and its contained charge, said accessory comprising a sealing diaphragm located interiorly of and across the tube and secured around its rim to the interior wall of the tube, and a rupturable portion made integral with the diaphragm to be part of the seal, said portion blowing out in one direction simultaneously with the blowing of the gas jet at the nozzle in case of inadvertent ignition of said charge.
3. In a rocket projectile having a motor tube containing a burnable charge; a sealing diaphragm across the interior of the tube at one end of said charge and having a rupturable portion, an annular flange erected from the diaphragm toward the charge, providing a shoulder and carrying said rupturable portion, and a compressible washer surrounding the rupturable portion and being mounted on the shoulder in contact with the diaphragm and burnable charge.
